US0D1000620S

(12) **United States Design Patent** (10) Patent No.: **US D1,000,620 S**
(45) Date of Patent: ** Oct. 3, 2023

(54) **STRESS RELIEVER GRIP RING**

(71) Applicant: **Xiongfeng Qiu**, Guangdong (CN)

(72) Inventor: **Xiongfeng Qiu**, Guangdong (CN)

(**) Term: **15 Years**

(21) Appl. No.: **29/774,620**

(22) Filed: **Mar. 18, 2021**

(51) LOC (14) Cl. **24-01**

(52) U.S. Cl.

USPC **D24/200**; D21/468
